UNITED STATES PATENT OFFICE.

HARRY S. BELLIS, OF WEBSTER GROVES, MISSOURI.

BOTTLE.

SPECIFICATION forming part of Letters Patent No. 784,099, dated March 7, 1905.

Application filed May 5, 1904. Serial No. 206,566.

To all whom it may concern:

Be it known that I, HARRY S. BELLIS, a citizen of the United States, residing at Webster Groves, in the county of St. Louis and State of Missouri, have invented certain new and useful Improvements in Bottles; and I do declare the following to be a full, clear, and exact description of the invention, such as will enable others skilled in the art to which it applies to make and use the same.

This invention relates to improvements in non-refillable bottles.

The object of the invention is to provide a bottle and a stopper for the same which will permit the contents of the bottle to be poured out, but which will prevent the refilling of the same without breaking some part of the bottle.

With this object in view the invention consists of certain novel features of construction, combination, and arrangement of parts, as will be more fully described, and particularly pointed out in the appended claims.

In the accompanying drawing is shown a vertical sectional view of a bottle and stopper embodying the invention.

Referring more particularly to the drawing, 1 denotes the bottle, 2 denotes the neck of the same, the lower portion of which is bulged or globular in form, as shown at 3. Above said globular portion the neck is shaped to form an annular groove or recess 4, and above said grooved portion is a cylindrical extension 5, forming the upper end of the neck. In the bulged or globular portion of the neck is arranged a check-valve 6, which is seated in the lower end of said globular portion, as shown, and thereby closes the bottle and prevents the refilling of the same. The valve 6 may be formed of rubber, glass, metal, or any suitable material, and is provided with an upwardly-projecting stem 7, which is adapted to slide upwardly or telescope into the lower tubular end of a guide-bar 8. In the side walls of the lower tubular-end of said guide-bar are formed vertically-disposed slots 9, with which are adapted to be engaged laterally-projecting vertically-disposed wings or ribs 10, formed on the upper end of the valve-stem 7, thereby guiding the valve-stem in its upward move-

ment and preventing turning of the same. A light coiled spring 12 is arranged on the valve-stem 7 between the valve 6 and the lower end of the guide-bar, thereby normally holding the valve down in closed position.

The upper end of the guide-bar 8 is secured to a bar 13, which is connected to the lower ends of vertically-disposed hangers or supporting-bars 14, the upper ends of which are connected to a frusto-conical-shaped baffle-plug 15, which fits closely in the cylindrical portion of the bottle-neck. In the plug 15 is formed a central vertical discharge opening or passage 16. Below the opening 16 in said plug and supported by the hangers or bars 14 is arranged a glass baffle-plate 17, which is of less diameter than the bottle-neck.

Between the baffle-plate 17 and the bar 13 is arranged a flat downwardly-curved leaf or ribbon-spring 18, the ends of which engage the groove or recess 4 in the neck of the bottle, thereby holding the parts of the stopper in the said neck.

Above the upper end of the conical plug 15 and over the hole 16 is arranged a circular downwardly-curved baffle-plate 19, said plate being supported above said plug by means of pins or bars 20. In the upper end of the bottle-neck, above the plate 19, is arranged a stopper 21, of cork, glass, or other suitable material, by which the bottle is sealed. The neck of the bottle, below the bulged or globular portion of the same, is of less diameter than the upper cylindrical portion of the same, thereby permitting the valve 6 to be inserted in the neck of the bottle and to seat itself against the sides of the bulged or globular portion 3, thereby closing the bottle at the top of the reduced portion of the neck.

After the bottle has been filled the valve 6 and the parts connected thereto are pushed into the neck of the bottle until the ends of the spring 18 snap into the groove or recess 4. The valve 6 will by this time have been seated in the lower end of the portion 3 of the neck and will be held down by the spring 12. The stopper 21 is now placed in the upper end of the bottle.

When it is desired to pour out any of the contents of the bottle, the stopper 21 is first

removed, and as the bottle is tilted the liquid in the same will push the valve 6 upwardly against the tension of the spring 12 and pass around the same and out of the bottle. As soon as the liquid is all out or the bottle turned to an upright position again, the spring will close the valve and prevent any more liquid from being placed into the bottle.

Any attempts to raise or tamper with the valve 6 will be frustrated by the baffle plug and plates above the same. Should an attempt be made to withdraw the baffle plug or plates from the bottle, the bar 13 will cause the spring 18 to straighten out, thereby firmly locking said parts in the neck of the bottle, which will be broken before these parts can be removed.

From the foregoing description, taken in connection with the accompanying drawing, the construction and operation of the invention will be readily understood without requiring a more extended explanation.

Various changes in the form, proportion, and the minor details of construction may be resorted to without departing from the principle or sacrificing any of the advantages of this invention.

Having thus fully described my invention, what I claim as new, and desire to secure by Letters Patent, is—

1. In a bottle of the character described, the combination with the neck of the same having a bulged or globular portion and a reduced portion below said globular portion, of

a check-valve arranged in said globular portion to close said reduced portion, an apertured frusto-conical baffle-plug arranged in the upper portion of said neck, baffle-plates arranged above and below said plug, and means whereby said parts are locked against removal from the neck of said bottle, substantially as described.

2. In a bottle of the character described, the combination with the neck of the same, having a bulged or globular portion, a reduced portion below said bulged portion, and an annular groove or recess above the same, of a valve seated in the lower end of said globular portion, thereby closing the entrance to the bottle, an apertured frusto-conical baffle-plug arranged in the upper portion of said neck above said globular portion, a baffle-plate arranged above said plug, a similar plate arranged below the same, banger-bars connecting said cross-bar with said plug, and a downwardly-curved spring resting on said cross-bar, the ends of said spring being adapted to engage the annular groove or recess formed in said neck, thereby preventing the withdrawal of the valve and the parts connected thereto, substantially as described.

In testimony whereof I have hereunto set my hand in presence of two subscribing witnesses.

HARRY S. BELLIS.
